UNITED STATES PATENT OFFICE.

EMERY ANDREWS, OF KENNEBUNK, MAINE, ASSIGNOR TO THE MOUSAM MANUFACTURING COMPANY, OF SAME PLACE.

MACHINE FOR FORMING HEEL-STIFFENERS.

SPECIFICATION forming part of Letters Patent No. 371,537, dated October 18, 1887.

Application filed February 17, 1887. Serial No. 227,915. (No model.)

To all whom it may concern:

Be it known that I, EMERY ANDREWS, of Kennebunk, in the county of York and State of Maine, have invented certain new and useful Improvements in Machines for Forming Heel-Stiffeners, of which the following, taken in connection with the accompanying drawings, is a specification.

My invention relates to machines for forming heel-stiffeners to the desired shape to fit the heel portion of the last, and particularly to that class of such machines in which a divided or sectional mold is used; and it consists in certain novel features of construction, arrangement, combination, and operation of parts, which will be readily understood by reference to the description of the drawings and to the claims to be hereinafter given.

Figure 1 of the drawings is a plan of a machine embodying my invention with the flange-turner and its support removed. Fig. 2 is a front end elevation of the same with a portion of the legs broken away. Fig. 3 is a vertical longitudinal sectional elevation, the cutting-plane being on line $\alpha\alpha$ on Figs. 1 and 2; and Fig. 4 is a partial plan with the mold closed upon the blank and in position to commence to turn the flange.

In the drawings, A is the bed of the machine, supported by the legs A', and provided upon its upper side with ways to receive the reciprocating carriages B and B', and with the side cheeks, C C, upon the upper edges of which are secured the boxes b b', in which are mounted the shafts D and D', respectively.

The shaft D has firmly secured upon one end thereof the driving-pulley D², and upon the other end the pinion D³, which meshes into and imparts motion to the gear-wheel D⁴, firmly secured upon the shaft D', which shaft has also secured upon its opposite ends the crank-disks c c, in each of which is set a crank-pin, d, upon which is fitted one end of the connecting-rod E, the opposite end of which is fitted to a journal formed upon the end of the bar F, firmly bolted to the upper side of the carriage B, as clearly shown in Figs. 1 and 2.

The carriage B has firmly secured upon its upper side the heel-shaped former G, and the carriage B' has firmly secured thereon the central section, H, of the stiffener-forming mold,

the forward end of said section being shaped to form a counterpart of the rear end portion of the heel-shaped former G, as shown in Figs. 1 and 3.

The carriage B' has pivoted to its upper surface the two arms I and I', in the forward end portions of which are formed concavities e, shaped to form counterparts of the side portions of the heel-shaped former G, as shown in Fig. 1. To the arms I and I' are pivoted the arms J and J', respectively, each carrying in its front end an anti-friction roll, f, and adjustable toward and from the arm I or I' by means of the screw g and check-nut h, as shown in Figs. 1 and 2.

To the inner faces of the cheeks C C, at their forward ends, are secured the plates L L, having their inner vertical surfaces at their front ends cam-shaped, as shown at i i in Fig. 1, against which the rolls f f bear when the carriage B' is at the extreme of its forward movement, and the arms I and I' are forced apart by the reaction of the spring M, as shown in Fig. 1.

N is a plate or bar extending across the machine from one cheek C to the other, above the stiffener-forming sectional mold, the same being firmly secured at its ends to the upper edges of the cheeks C C by suitable bolts, as shown.

O is the flange-turning plate, having formed in its front end the V-shaped notch j, and being suspended from the plate or bar N by the screws k k, which are fitted to threaded holes in the plate N and connected to the plate O by a swivel attachment in such a manner that the plate O may be adjusted vertically by turning the screws k k in an obvious manner.

The carriage B' is moved toward the front end of the machine, or toward the left-hand end of Fig. 3, by means of the weight P, attached to one end of the cord l, which, after passing over the pulley m, has its other end attached to the eyebolt n, screwed into the under side of the carriage B', near its rear end, the forward movement of said carriage B' being arrested at the proper point by the pin o, set in the under side of said carriage, coming in contact with a pin, p, set in the bed A, all as shown in Fig. 3.

The operation of my invention is as follows:

The several parts being in the positions shown in Figs. 1 and 3 of the drawings, a stiffener-blank is placed by the operator between the rear end of the former G and the front ends of 5 the side sections of the mold, with its straight edge uppermost and projecting above the upper surface of the former a distance equal to the width of flange that it is desired to have formed upon the stiffener, and with the center 10 of the length of the blank coinciding with dotted line α α , in which position it is held until, by the rotation of the shaft D' and crank-disks c, the former G has moved toward the rear a sufficient distance to press the blank into the 15 curve of the front end of the central section, H, of the divided mold, and firmly clamp said blank between said central section of the mold and the rear end of the former, when a continuation of the rearward motion of the carriage B 20 and the former G causes a corresponding rearward movement of the carriage B' and the divided or sectional mold attached thereto, and by the rearward movement of the rolls f f along the curved surfaces i of the plates L L 25 the side sections, e e, of the mold are closed upon the blank to press it hard upon the former G, as shown in Fig. 4. A further continuation of the rearward motion of the carriages B and B', carrying therewith the former and 30 mold, with the blank clamped between them, causes the portion of the blank which projects above the upper surfaces of the former and mold to be turned inward upon the upper surface of said former and pressed hard thereon 35 to form the heel seat or flange of the stiffener by the action thereon of the V-shaped front end of the stationary flange-turning plate O. When the former is returning to the position 40 shown in Figs. 1 and 3, after having completed the forming of a heel-stiffener, and when it has nearly reached the extreme of its forward movement, the stiffener is removed from said former and another blank is placed in position to be formed by the next rearward 45 movement of said former.

The cam-plates L i have inserted between them and the cheeks C C sheets of rubber r, so as to render them slightly yielding to compensate for slight variations in the thickness 50 of different blanks in the same lot or in different parts of the same blank.

Above the end portions of the plate N, and between it and caps N', are placed pieces of rubber s, so as to render said plate N and the 55 flange-turning plate O slightly yielding when the pressure is increased beyond a given point by inequalities in the thickness of the stock, the rubber pieces r and s all being compressed to the proper degree of tension 60 to resist any desired pressure without yielding by the bolts r' and s', respectively; but if by an increased thickness of the stock in any part the pressure is increased beyond said desired or predetermined pressure the cam- 65 plates L i or the plates N and O will yield sufficiently to prevent injury to the blank.

What I claim as new, and desire to secure by Letters Patent of the United States, is—

1. The combination of a reciprocating heel-shaped last or former, a sectional mold composed of three parts, two of which are movable toward and from each other and relative to the third or central part, and all of the parts of said sectional mold being movable by and with said former during a portion of its reciprocation, a stationary flange-turning plate having a notched operating end, and mechanism, substantially as described, for reciprocating said former and closing the side sections of the mold upon the former. 70 75

2. The combination of the carriage B, having mounted thereon the former G, mechanism, substantially as described, for imparting to said carriage and former a reciprocating movement, the carriage B', the sectional mold H e e, mounted upon and movable with said carriage B', suitable ways for guiding said carriages B and B', the weight P, cord l, and pulley m for moving the carriage B' toward the carriage B, and the stop-pins o and p, all constructed, arranged, and operating substantially as described. 85 90

3. The combination of the carriage B, the heel-shaped former G, mounted upon and movable with said carriage, mechanism, substantially as described, for reciprocating said carriage and former, the carriage B', the sectional mold H e e, mounted upon and movable with said carriage B', suitable ways for guiding the carriages B and B' in their reciprocations, the stationary notched flange-turning plate O, the weight P, the cord l, the pulley m, and the stop-pins o and p. 95 100

4. The combination of the carriage B, the former G, mechanism, as set forth, for reciprocating said carriage and former, the carriage B', arranged to be moved in one direction by the carriage B and former G, the central part, H, of a sectional mold secured in a fixed position upon said carriage B', the arms I and I', pivoted to said carriage B' and each carrying at its free end a side section, e, of the sectional mold, the arms J and J', pivoted to the arms I and I', respectively, and each carrying at its free end a roll, f, and the fixed 110 cams L i L i, all arranged and adapted to operate substantially as described. 115

5. The combination of the two independent carriages B and B', mechanism, substantially as described, for imparting thereto a reciprocating movement, the former G, secured upon the carriage B, the sectional mold H e e, and the arms J J', carrying the rolls f f, the cam-plates L i L i, and the elastic cushions r r, interposed between said plates and the cheeks 120 C C, substantially as described. 125

6. The combination of the two independent carriages B and B', suitable ways for guiding the same, mechanism, substantially as described, for imparting to said carriages a reciprocating motion, the former G, secured upon the carriage B, the sectional mold H e e, 130

mounted upon the carriage B', the plate or bar N, the bolts s' s' for securing said bar to the cheeks C C, the elastic cushions s s, interposed between the heads of said bolts and said bar, 5 and the flange-turning plate O, adjustably suspended from said bar N, substantially as described.

In testimony whereof I have signed my name

to this specification, in the presence of two subscribing witnesses, on this 16th day of Febr- 10 ary, A. D. 1887.

EMERY ANDREWS.
